HOT AIR FURNACE

Richard C. Jaye and John F. Hirtz, Watertown, Wis., as signors to Syncromatic Corporation, Watertown, Wis., a corporation of Wisconsin

Filed May 31, 1960, Ser. No. 32,798

13 Claims. (Cl. 126—116)

This invention relates to furnaces and has more particularly reference to gas-fired hot air furnaces for residential use.

In general, it is an object of the invention to provide a hot air furnace with components that are designed to greatly facilitate manufacture and assembly of the furnace at very low cost, and which features a heating unit that assures the transfer of heat to air flowing thereover far more efficiently than is the case with conventional heating units, though requiring considerably less metal for any given B.t.u. output.

More specifically, it is an object of the invention to provide a hot air furnace of the character described with an improved heat exchanger unit featuring primary and secondary heat radiating and transfer means through which combustion gases flow before discharging to a flue, and wherein novel baffle means incorporated in said heat radiating and transfer means assures substantially uniform flow of combustion gases over all the interior surfaces of said secondary heat radiating and transfer means and the most efficient transfer of heat thereby to air circulated over its exterior surfaces.

With these and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

FIGURE 1 is a side elevation of a gas-fired furnace embodying this invention, with wall portions of its casing broken away to show interior details of construction;

FIGURE 2 is a front elevational view of the furnace with its front covers removed and with portions thereof broken away to illustrate details of construction;

FIGURE 3 is a cross sectional view taken through FIGURE 2 on the plane of the line 3—3.

FIGURE 4 is a perspective view of the heat exchange unit incorporated in the furnace, viewing the same from the rear;

FIGURE 5 is a fragmentary sectional view taken through FIGURE 2 on the plane of the line 5—5.

FIGURE 6 is an enlarged fragmentary sectional view taken through FIGURE 1 on the plane of the line 6—6; and

FIGURE 7 is a fragmentary perspective view illustrating the manner in which the back draft deflector is mounted on the furnace casing.

Referring now more particularly to the accompanying drawings, in which like reference characters have been applied to like parts throughout the several views, the numeral 10 generally designates the upright casing of a gas-fired hot air furnace. The casing has rectangular vertically elongated opposite side walls 12 joined at the rear of the furnace by a back wall 13. Short inturned flanges 14 extend along the upright front edges of the side walls, and these flanges terminate in short rearwardly directed legs 15 which are parallel to the side walls. The space between

2

the legs 15 provides a wide opening in the front of the casing, which is partially closed conjointly by three cover sections located one above the other. These cover sections comprise an upper section 16, a lower section 17, and a foraminous intermediate cover section 18 in the form of an expanded metal grille.

In the furnace illustrated, a horizontal shelf 19 is fixed in the casing at an intermediate level, to divide its interior into a blower compartment 20 in the space beneath the shelf, and a heating compartment 21 in the space above the shelf. A blower 22 is mounted in the blower compartment 20 in a manner to be described later, to force air to be heated upwardly into the heating compartment 21 through a hole, not shown, in the shelf.

It should be understood, however, that this invention does not depend upon any particular location of the blower compartment. Persons skilled in the art will appreciate that the blower compartment may be above the heating compartment, or even to one side of it if low height of the furnace is an important consideration.

As stated, the space inside the casing above the shelf 19 provides the heating compartment 21, which as is customary opens through the top of the casing for connection with a heat delivery duct, not shown. The heating compartment, of course, is defined in part by the side walls 12 and the back wall 13 of the casing. The front of the heating compartment is defined by an upright panel or face plate 24, which extends transversely across the inside of the casing a short distance inwardly from the front thereof. The panel 24 has a short rearwardly directed flange 25 at its bottom resting upon the shelf 19, and its upper end terminates adjacent to the top of the casing. It also has short rearwardly directed flanges 26 extending along its opposite side edges, and the panel constitutes the widest part of a subassembled heating unit generally designated 27.

The heating unit is designed and proportioned to enable the entire unit, including the panel or face plate 24, to be assembled into the casing through the front thereof. For that purpose, the transverse dimension between the legs 15 on the side wall flanges 14 is slightly larger than the distance between the side flanges 26 on the face plate of the heating unit, to enable it to be easily passed therebetween.

One of the features of the furnace of this invention resides in the simplicity and ease with which the face plate of the heating unit may be secured in position within the casing 10. As stated previously, its bottom flange 25 rests upon the shelf 19, and it is held firmly in position upon the shelf by its engagement under the free forwardly projecting end portion of a spring finger 28 which has its base 29 seating flatwise upon the shelf behind the flange 25 and secured thereto as by spot welding or the like. The spring finger clamp 28—29 which firmly holds the flange 25 down against the shelf may extend entirely across the interior of the casing, or it may comprise a plurality of shorter, transversely spaced fingers if desired.

Also forming part of the means by which the face plate is secured in position within the casing are a pair of rails, 60 generally designated 30. These rails have attaching legs 31 which flatwise overlie and are permanently secured to the opposite side walls 12 of the casing, with the rails extending vertically therealong ahead of the face plate 24. The rails are also provided with inwardly directed flanges 65 32 against which the face plate flatwise abuts, and narrow channels 33 formed in these flanges are positioned to receive the side flanges 26 on the face plate, as shown best in FIGURE 3, to preclude edgewise transverse motion of the face plate relative to the casing.

As will be apparent from FIGURE 3, a more or less sealed connection between the side flanges on the face

plate and the inwardly directed flanges 32 of the rails can be afforded by adhering gummed tape around the rearwardly directed face plate flanges and snugly wedging the taped flanges in their channels 33.

Only four sheet metal screws are required to securely fasten the face plate in position within the front portion of the casing. An upper pair of screws 35 pass through the opposite side portions of the face plate at a location a distance downwardly from its top, and thread into the flanges 32 on the rails 30. A lower pair of screws 36 likewise pass through opposite side edge portions of the face plate and thread into the flanges 32 on the rails at a location near the bottom of the face plate.

The heating unit 2 includes a heat exchanger 38 fabricated from sheet metal, and the design thereof constitutes one of the most important features of this invention. The heat exchanger, of course, is located in the heating compartment 21 and it is secured to the back of the face plate in a manner to be described shortly. It comprises a vertically elongated main heating section 40 and a pair of upright but smaller heating sections or radiators 41 disposed at opposite sides of the upper portion of the main heating section. As seen best in FIGURE 1, the main heating section has a more or less rectangular shape when viewed from the side, with its height substantially twice its fore and aft dimension.

The bottom portion of the main heating section provides a horizontally elongated combustion chamber 42 extending from the rear of the face plate 24 to nearly the back wall 13 of the casing. The main heating section also includes an upper chamber 43 extending lengthwise above the combustion chamber at the top of the heating compartment, and a duct-like intermediate portion 44 extending between and joined to the upper and lower chambers 43 and 42, respectively, to rigidly connect the same together with their interiors in communication with one another. A substantially large diameter cylindrical collar 45 protruding from the front of the combustion chamber into a hole 46 in the lower central portion of the face plate, and welded in place in said hole, provides both an air inlet for the combustion chamber as well as an access port through which a gas burner 47 may be projected into the interior of the combustion chamber.

The bottom portion of the combustion chamber has a semi-cylindrical configuration coaxial with the collar 45 and of the same diameter. It merges with opposite side wall portions 48 which extend tangentially upwardly from the combustion chamber only a short distance above the level of the top of the collar. Thus, the combustion chamber may be said to be open at its top all along the fore and aft dimension of the chamber. The upper edges of the side walls 48 of the combustion chamber join edge-wise with the lower ends of flat side walls 49 on the upright duct 44, but it will be noted that the walls 49 converge toward the upper chamber 43 and connect with the bottom of the latter through a short duct section 50. The upper duct section 50 has parallel upright side walls 51 joined in an opening 52 in the upper chamber that extends along the entire bottom thereof.

With this arrangement, it will be seen that hot gases resulting from the combustion of gaseous fuel in the combustion chamber rise upwardly in the duct 44 to flow into the bottom of the upper chamber 43, but it will be observed that the upper chamber is widened and has opposite vertically extending side walls 53 which are parallel to the sides 48 of the combustion chamber and to the side walls 12 of the casing, and which are offset outwardly from the opposite sides of the upper duct section 50.

The walls of the upper chamber 43, of course, provide secondary heat radiating and transfer surfaces, while those of the combustion chamber and the duct 44 afford primary heat radiating and transfer surfaces.

The upper chamber 43 extends for and aft within the upper portion of the heating compartment, and it has a

substantially rectangular cross section, with somewhat greater height than width. Transversely opposed outlet collars 55 fixed in suitable openings in the medial portions of its side walls 53 and projecting outwardly therefrom provide ports to enable hot combustion gases entering the bottom of the upper chamber 43 to exit therefrom after first being circulated around the interior of the latter, in intimate contact with the walls thereof. For this latter purpose a baffle structure generally designated 57 is fixed inside the upper chamber. It comprises an elongated flat strip 58 of metal having its lower end portion projecting into and welded in place within the top of the upper duct portion 50, and its upper end abutting and welded to the top of the upper chamber 43. Its flat sides are disposed normal to the side walls 53 of the upper chamber, but its opposite side edges 59 are spaced a distance therefrom, as seen best in FIGURE 6.

It will be noted that the strip 58 is located in a vertical plane which contains the common axis of the outlet collars 55 of the upper chamber, and that a pair of oppositely curved deflectors 60 is secured to the opposite faces of the strip at locations within the upper end of the upper duct section 50, and the upper portions of the deflectors diverge in fore and aft directions and extend into the wider bottom portion of the upper chamber. Because of their shape and location, therefore, the deflectors more or less direct equal quantities of the hot combustion gases entering the upper chamber 43 forwardly and rearwardly along the lower portion thereof and cooperate with the divider strip 58, to assure that the gases will sweep across all of the interior surfaces of the upper chamber, both forwardly and rearwardly of the divider, before they converge on the divider and discharge in opposite lateral directions from the outlets 55 of the chamber.

The combustion gases leaving the upper chamber 43 flow into the auxiliary heating sections or radiators 41 at opposite sides of the upper chamber 43, where more heat is abstracted therefrom. The auxiliary radiators are identical except that they are of right and left construction. They extend vertically fore and aft in the heating compartment and are substantially shallow or narrow in their dimensions which are transversely of the casing.

When viewed from the side, as seen in FIGURE 1, the hollow auxiliary radiators 41 have a substantially rectangular shape, with their fore and aft dimension substantially equal to that of the duct 44 and the combustion chamber therebeneath, and a vertical dimension which is substantially greater than that of the upper chamber 43 and nearly one-half the total height of the main heating section 40. At its side facing the adjacent upper chamber 43, each of the auxiliary radiators is provided with an inlet opening 62 in which the outlet collars 55 on the upper chamber are fixed so that the radiator is rigidly joined to the upper chamber by said collars.

The inlets 62 of the auxiliary radiators are located in the upper central portions of their inner sides, so that a substantial portion of each radiator extends both fore and aft as well as downwardly from the inlet. Short outlet collars 63 at the upper front corners of the auxiliary radiators provide discharge ports through which combustion gases exit therefrom, and the collars project forwardly into and are welded within similarly shaped holes in the front panel 24 to enable combustion gases to be discharged into a zone in the upper front portion of the casing, ahead of the face plate 24.

Since the discharge ports provided by the outlet collars 63 are substantially close to the inlets 62 thereof and substantially at the same level, means must be provided to prevent combustion gases entering the auxiliary radiators from discharging directly to their outlet ports, without first contacting all of the wall surfaces of the radiators to enable the extraction of all of the heat possible from the gases. Novel baffle means, generally designated 65, is provided for this purpose, one such baffle means being located inside of each of the radiators.

The baffle means 65 in each auxiliary radiator 41 comprises a dismountable upper baffle section 66 and a fixed lower section 67. The baffle section 66 comprises a substantially elongated rectangular plate-like strip of metal supported in the upper front portion of the auxiliary radiator and dismountable through the outlet collar 63 thereof. It edgewise bridges the narrow dimension of the radiator and extends downwardly from its top at a location intermediate the inlet 62 and outlet 63 thereof. The upper portion of the strip extends forwardly through the outlet collar 63, at the top thereof, and has a tab 68 bent upwardly therefrom to lie flatwise against the front of the face plate. This tab extends upwardly into a narrow downwardly opening channel 69 formed integrally with the top of the face plate and extending transversely thereacross, to releasably hold the upper front portion of the baffle section 66 in position within the radiator. Preferably, the baffle section 66 extends downwardly and rearwardly away from the outlet collar to a level at least even with the lower edge of the inlet 62 of the radiator.

If desired, of course, the baffle section 66 could be disposed more or less vertically within the auxiliary radiator, although its position intermediate the inlet and outlet openings of the radiator is essential since it then may be relied upon to block direct passage of incoming gases to the outlet collar 63. The side edges of the baffle section 66, of course, are contiguous to the opposite side walls of the auxiliary radiator.

The lower baffle section 67 comprises a substantially flat body plate 71 which extends fore and aft within the lower portion of the auxiliary radiator, beneath the inlet 62 thereof. It is permanently secured in a laterally tilted position within the radiator, as by tack welding, with its lower edge near the bottom of the radiator and in continuous contact with inner side wall (having the inlet 62). The upper edge of the body plate is in continuous engagement with the outer side wall of the radiator and at about the same level as the bottom of the inlet 62.

The forward end of the plate 71 is vertical and disposed a distance rearwardly from the front of the radiator but ahead of the inlet 62 and substantially in line with the lower end of the inclined upper baffle section 66. Its rear edge however is disposed adjacent to the rear of the radiator, but it is slanted downwardly and forwardly toward the bottom of the plate, as indicated at 72.

The body plate 71, therefore serves to divide a substantial part of the lower portion of the auxiliary radiator into a pair of laterally adjacent compartments, namely, an inner compartment 73 and an outer compartment 74, with the compartments located at opposite sides of the plate. The two compartments are communicated with one another around the tapered rear edge 72 of the plate, but they are closed off from one another at the front of the plate by a flange or partition 76 on the front end of the plate, extending laterally inwardly therefrom and abutting the inner side wall of the radiator.

To facilitate its attachment, the flange 76 may be provided with an attaching lip 77 bent forwardly therefrom and flatwise secured to the inner side wall of the radiator, as by tack welding, to close the front of the inner compartment 73.

The flange 76 is spaced a substantial distance from the front of the auxiliary radiator, and its upper edge serves as a seat upon which the lower end of the inclined upper baffle section 66 is readily detachably supported so as to form, in effect, a continuation of the flange 76.

Due to the cooperation between the upper and lower baffle sections, and because communication between the rear of the outer compartment and the inlet portions of the radiator is substantially restricted, combustion gases entering the upper or inlet portion of the radiator cannot flow freely into the outer compartment 74 and are thus caused to spread out into and sweep across all areas of the upper portion of the radiator as well as of the inner compartment 73, to effectively heat those portions

thereof which are in heat transfer relation to air to be heated.

Since combustion gases entering the radiator must flow through the outer compartment 74 in order to reach the outlet of the radiator, such gases are thus constrained to flow downwardly and rearwardly around the tapered rear edge 72 on the lower baffle section, then forwardly through the outer compartment 74 into the space ahead of the flange 76 on the lower baffle section, from whence they may travel upwardly to and discharge from the outlet collar 63.

The particular disposition of the baffle means in each auxiliary radiator, as described above, assures intimate contact between the combustion gases entering the radiator and substantially all of the walls of the radiator before such gases are discharged therefrom. This achieves very efficient heat transfer between such gases and air circulated over the exterior of the radiator, with a minimum of sheet metal employed in the radiators.

It is important to note that with the baffle construction described, combustion gases flow faster through the smaller outer compartment 74 than through the larger inlet section of the radiator, to thus compensate as much as possible for the differences in area between their respective heat transfer surfaces and materially contribute toward uniform heating of all portions of the radiator.

Also, since the effective cross sectional area of the outer compartment 74 decreases progressively from the bottom of the radiator toward the top of the body plate 71, combustion gases would ordinarily flow through the narrow upper portions of the outer compartment, without coming into the transfer relationship with the walls thereof at its wider lower portion. The downwardly and forwardly tapering rear edge 72 on the body plate of the lower baffle section, however, effects proper distribution and control of the flow of combustion gases through the outer compartment 74 by reason of the fact that it progressively restricts the entrance to the outer compartment toward the narrower upper portions thereof, causing progressively increasing volumes of gases to be forced into the wider lower portions of the outer compartment.

As a result, the tapered rear edge 72 of the lower baffle section exerts a metering effect by which gas flows at substantially uniform velocity through all levels of the outer compartment of the radiator, to assure uniform heating of the adjacent outer wall of the radiator to nearly the same degree as the walls of the radiator which define the inlet portions thereof.

As stated previously, the upper edge of the partition or flange 76 on the front end of the lower baffle section provides a seat upon which the lower end of the upper or inclined baffle section 66 is readily detachably supported. In order to removably hold the lower end of the upper baffle section against accidental displacement, a tab 78 is struck forwardly from its lower end to engage in front of the upper edge portion of the flange 76, while legs 79 at either side of the tab engage the upper rear of the flange.

Attention is directed to the fact that the main heating section 40 as well as each of the auxiliary radiators 41 are formed from only two more or less shallow but mating pan-like sheet metal section fixed together by a welded seam 81 that extends continuously about their mating edges. Their design, moreover, is such as to permit their being die-drawn and secured together by a minimum of welding, as distinguished from more conventional constructions involving press braking or rolling, or the use of a multiplicity of die-drawn sections.

Not only does this design of the various sections of the heat exchanger enable their manufacture at low cost, but it allows modular assembly thereof into various combinations of main and auxiliary sections in order to vary the B.t.u. output of the furnace. By way of example, in a furnace designed for a relatively low B.t.u. output, only 75 a main heating section 40 would suffice, and the auxiliary

radiators would be omitted. In that case, of course, the upper chamber 43 would be formed with imperforate opposite side walls, and a discharge port or outlet collar (not shown), similar to the collar 63 on each auxiliary radiator, would be fixed in its front end.

As another example, two such main heating sections 49 could be fixed in side by side relationship to the back of the face plate 24 of the heat exchanger unit, with a gas burner for each of the combustion chambers of the section. Each of the upper chambers 43 would have a suitable discharge port provided in its front, and the upper chambers would also be communicated with one another as by a collar 55 such as employed to connect the upper chamber with each auxiliary radiator in the embodiment disclosed in the drawings.

In a reduced output furnace, it might suffice to provide only one auxiliary radiator 41, while in a furnace having two main heating sections 49, as many as three auxiliary radiators could be used to advantage for most efficient heat radiation and transfer to air circulated over the exterior surfaces of the heat exchanger.

In addition to being supported by the front panel 24, the main heating section is additionally supported at its rear upon the shelf 19, as by means of a short length of angle iron 83 welded to the underside of the combustion chamber and having a horizontal flange to seat flatwise upon the shelf. A strap 84 also extends across the rear of the heat exchanger, adjacent to the bottom of the auxiliary radiators, and is welded to both of the latter and to the rear of the duct section 44 to lend rigidity to the unit.

The combustion gases which discharge from the auxiliary radiators 41 are received in a boxlike collector 86 attached to the upper front portion of the face plate 24, over the combustion gas outlet ports therein. The entire bottom of the collector is open, but it has a front wall 87 parallel to the face plate or panel 24 and substantially flush with the front edges of the casing, and opposite side walls 88 bent rearwardly from the side margin of the front wall but diverging toward the panel 24. The rear edges of the side walls are turned inwardly, as at 89, to provide vertically extending flanges that seat flatwise upon the opposite marginal portions of the panel. A horizontal wall 90 closes the top of the collector, and a short upstanding flue collar 91 is secured in the top wall to adapt the collector for attachment to a flue.

The collector is secured in position on the upper front portion of the front panel 24 in an exceedingly simple manner. For this purpose, an upstanding flange 93 is formed along the rear of the collector top wall, coplanar with the side flanges 89. This flange projects upwardly into and fits within the narrow transverse channel 69 on the top of the face plate, to be more or less snugly confined therein together with the tab 68 on the upper baffle section 66.

The lower portion of the collector is secured to the front panel 24 of the heating unit by means of the upper pair of sheet metal screws 35, which also pass through the side flanges 89 of the collector near its bottom, and thread into the rails behind the panel 24. It is a feature of this invention that the collector side flanges 89 cooperate with transversely opposite downwardly and forwardly angled notches 95 in the legs 15 of the side wall flanges 14 to provide a simple and readily detachable mounting for a diverter baffle 96 in a position beneath the open bottom of the collector. The diverter baffle extends downwardly and forwardly from the bottoms of the collector flanges, and its purpose is to divert air forwardly out of the casing away from the discharge ports of the auxiliary radiators, in case of sudden back drafts.

The baffle or diverter 96 is supported in the desired inclined position beneath the open bottom of the collector by having its lower edge received in the transversely opposite notches 95 on the side wall flanges. Its upper end rests against the face plate, and an upstanding flange 98 on the upper end of the baffle is clamped between the

face plate and the lower end portions of the collector flanges by the screws 35 to hold the top of the diverter in place.

In order to enable the screws 35 to firmly hold the collector flanges flatwise against the face plate, the lower end portions of the collector flanges are separated from the collector side walls by slits 99, and the diverter flange 98 fits only behind the free end portions of the collector flanges, beneath the screws 35.

At its lower end, an intermediate portion of the diverter baffle is bent therefrom to form a narrow upwardly opening channel 101 to receive a downwardly directed lip 102 on the upper end of the grille 18, so as to suitably suspend the grille therefrom. Since the lip 102 on the grille extends transversely between the legs 15 on the side wall flanges, the upper end of the grille is held against all but vertical detaching motion by its connection with the lower end of the diverter.

The lower end of the grille also has a downwardly directed lip 103 at its rear which hooks over an upstanding flange 104 on the front end of the shelf 19, to thus cooperate with the diverter engaging lip 102 in readily removably holding the grille in position upon the casing.

To detach the grille 18, it is only necessary to grasp it at its opposite side edges and lift it upwardly a short distance to disengage its upper and lower lips from the casing carried parts that normally hold the grille in place on the casing.

The lower cover 17 also has a hook 106 that engages over the upstanding flange 104 on the shelf 19, beneath the lip 103 on the grille, to be thereby detachably suspended from the front of the casing.

As is customary, fuel supplied to the gas burner 47 passes through a main control valve 108 which acts to close off the flow of gas to the main burner in the event of failure of a pilot burner 109 for the main burner. The pilot burner 109 may be mounted directly on the side of the main burner, as shown.

The main burner is supported conjointly by the face plate 24 and the bottom of the combustion chamber, as shown, and it includes an elongated mixing tube 110 which projects forwardly through the front of the combustion chamber and the face plate 24, as seen best in FIGURE 1.

The front end of the mixing tube is flared outwardly and forwardly so as to be substantially bell or trumpet shaped, and at its forward extremity it has a stationary air shutter disc 113.

As is customary, the shutter disc 113 has butterfly openings 116 at diametrically opposite sides of the hole. These butterfly openings cooperate with similar butterfly openings in a rotatable air shutter disc 117 flatwise contiguous to the rear face of the stationary disc.

A nipple 123 having one end threaded into the outer end of a fitting 122 that is connected to the front of the mixing tube and having its other end threaded into the outlet of the main valve 108, serves to mount the main valve on the front of the burner mixing tube 110 in a stable fashion. With the construction described, the entire gas burner and the main valve constitute an assembly which can be installed in the furnace as a subassembled unit to save considerable time and expense in the manufacture of the furnace.

The blower 22 is secured to the underside of the shelf 19 with the duct-like discharge mouth 125 of the blower projecting upwardly and in register with a correspondingly shaped opening, not shown, in the shelf. The mounting means for the blower includes a pair of elongated cleats 127 welded to the underside of the shelf, and extending fore and aft adjacent to opposite sides of the opening in the shelf. Each cleat has a downwardly stepped or offset portion which provides a vertical leg 128 and a horizontal ledge 129 extending inwardly from the bottom of the leg. The ledges 129 are coplanar

and spaced equal distances below the shelf 19, and they cooperate with their respective legs 128 to afford drawer-like guides which slidably receive cooperating protuberances 130 on the opposite sides of the blower discharge duct to enable the blower to be slid to and from its operative position seen in FIGURE 1 much in the manner of a drawer, thus facilitating the installation on and removal of the blower from the shelf.

The cleats 127 are preferably spot welded or otherwise permanently affixed to the underside of the shelf 19, and in cooperation with the underside of the shelf, their legs 128 and ledges 129 form channels which open toward one another.

According to this invention, the protuberances 130 on the opposite sides of the blower discharge duct are resilient, being provided by cylindrical rubber cushions or pads suitably mounted on the opposite side walls of the discharge duct as by means of studs, not shown. Also, their diameter is such as to enable them to be snugly but slidably received in the space between the underside of the shelf and the horizontal flanges of the channels provided by the ledges 129.

A felt sealing strip 134 or a similar sealing device is preferably clamped against the underside of the shelf by each cleat 127, as by an offset intermediate retaining portion 133, and the inner edges of the strips abut the opposite sides of the blower discharge duct.

With the construction described, the blower can be slid into the blower compartment from the front of the furnace much in the manner of a drawer. It will be understood, of course, that the guides or channels in which the cushioning pads 130 are received are open at their forward ends at the time of assembly of the blower into the casing. The ledges may be bent upwardly, as at 135, at their rear ends to provide stops with which the rubber cushioning pads engage to define the rearmost position of the blower within its compartment. After the blower is in position in the blower compartment, however, the forwardly projecting front portions of the ledges 129 may be bent upwardly ahead of the foremost cushions, as at 136, to prevent forward motion of the blower relative to the casing.

This manner of mounting the blower in the furnace casing is not only simple and inexpensive, but it achieves a cushioned suspension of the blower by which vibration thereof during its operation is damped in all directions to preclude transmission of such vibration to the casing walls.

Air to be heated may be introduced into the blower compartment through either side wall 12, or through the back wall 13 of the compartment. In either event, a conventional filter 137 is interposed between the air inlet opening in the blower compartment and the inlet of the blower.

From the foregoing description taken together with the accompanying drawings, it will be apparent to those skilled in the art that this invention provides a hot air furnace which features a heat exchanger which, because of its high efficiency, may be fabricated from considerably less sheet metal for a given B.t.u. output than was possible heretofore; and wherein unique means for mounting the collector, the diverter and the blower on the furnace casing results in reduced manufacturing and assembly costs.

What we claim as our invention is:

1. In a hot air furnace: a casing including upright opposite side walls connected by an upright back wall; an upright face plate extending across the interior of the casing a distance rearwardly of the front of the casing, and connected to the side walls so as to cooperate with them and the back wall in defining a heating compartment in the space enclosed thereby, said face plate extending to the top of the casing and having means on its upper end providing a substantially narrow channel that extends transversely across the top of the casing and opens downwardly directly ahead of the plane of the face plate, and said face plate having a flue gas discharge port in an

upper portion thereof; a heat exchanger in said compartment including a combustion chamber in which fluid fuel may be burned, and flue gas discharge means communicating with said port to conduct combustion gases out of the heat exchanger and into a zone ahead of the face plate; a back draft deflector extending across the interior of the casing ahead of the face plate and beneath said zone; means on the front portions of the side walls engaging the lower edge portions of the draft deflector for supporting the same from the casing in an upwardly and rearwardly inclined position with its upper edge adjacent to the face plate and at a level beneath the flue gas discharge port therein; a flue gas collector in the upper front portion of the casing, ahead of the face plate and above said deflector, said collector defining a chamber encompassing the zone into which combustion gases flow from said flue gas discharge port, being open at its bottom, having a top wall provided with an opening through which flue gases leave the chamber, and having opposite side flanges that overlie the front of the face plate at locations at opposite sides of the flue gas discharge port therein; means securing the collector to the face plate comprising an upstanding flange on the top wall of the collector at the rear thereof, confined in said narrow channel on the upper end of the face plate, and fastening devices, one at each side of the collector near the bottom thereof, securing the collector flanges to the face plate; and interengaging means on the collector and the deflector holding the upper portion of the latter against movement away from the face plate.

2. The hot air furnace of claim 1, wherein said interengaging means on the collector and deflector comprises a flange on the upper portion of the deflector confined between the lower end portions of the collector side flanges and the front of the face plate and clampingly held therebetween by said fastening devices.

3. The hot air furnace of claim 2, wherein said fastening devices are screws that pass through portions of the collector side flanges which are located above the deflector flange, and wherein the collector has lower portions of its side flanges separated from the adjacent walls of the deflector by slits to enable the collector flanges to be pulled tight against the front of the face plate at areas above the deflector flange by said screws.

4. The hot air furnace of claim 1 further characterized by the provision of: a baffle in the heat exchanger having an upper portion which extends forwardly through the top of said flue gas discharge port; and means detachably mounting said baffle in the heat exchanger comprising an upwardly directed tab on the upper end of said baffle, overlying the front of the face plate and engaged in said substantially narrow channel on its upper edge so as to be confined in said channel together with the flange on the top wall of the collector.

5. The hot air furnace of claim 1, wherein said face plate has an opening in its lower portion through which air necessary to support combustion enters the combustion chamber; a grille covering a front portion of the casing ahead of the face plate and extending transversely across the casing, and through which air enters the front portion of the casing for flow into the combustion chamber; and means mounting said grille on the front of the casing, comprising a lip on the lower end of the deflector defining a substantially narrow upwardly opening groove that extends transversely across the lower end of the deflector, and a downwardly directed flange on the upper end of the grille releasably hooked into said groove.

6. In a hot air furnace: a casing including upright opposite side walls connected by an upright back wall, and inwardly directed flanges on the upright front edges of the side walls; an upright face plate extending across an upper portion of the interior of the casing in spaced relation to the side wall flanges and cooperating with the back and side walls to define a heating compartment in the casing, said face plate having an air inlet opening in a lower central portion thereof and having a flue gas dis-

charge port in an upper portion thereof; a substantially horizontal shelf in the interior of the casing beneath said face plate, defining the bottom of the heating compartment, said shelf extending out to the flanged front edges of the casing side walls and being fixed to the side and back walls to rigidly connect them together; a heat exchanger in said compartment at the rear of the face plate, said heat exchanger including a combustion chamber which is supplied with air necessary to support combustion through said air inlet opening in the lower portion of the face plate, and said heat exchanger including forwardly extending flue gas discharge means communicating with said port in the upper portion of the face plate to discharge combustion gases into a zone in the front of the casing ahead of the face plate; a back draft deflector extending across the casing ahead of the face plate and beneath said zone; means on the flanged front edge portions of the side walls engaging the lower edge portion of said draft deflector for supporting the same from the casing in an upwardly and rearwardly inclined position with its upper edge adjacent to the face plate and at a level beneath the flue gas discharge port therein; a flue gas collector in the upper front portion of the casing ahead of the face plate and over said deflector, said collector defining a chamber encompassing the zone into which combustion gases flow from said flue gas discharge port, being open at its bottom, having a top wall provided with an opening through which flue gases leave the chamber, and having opposite side flanges that extend vertically along the front of the face plate at locations at opposite sides of the flue gas discharge port therein; means securing the face plate in position within the front portion of the casing comprising rails behind the face plate, fixed to the opposite side walls of the casing and having narrow vertically extending forwardly opening channels therein, rearwardly projecting flange means on the opposite upright edges of the face plate snugly received in said channels in the rails, an upper pair of fastening devices, one at each side of the collector near the bottom thereof, engaging said rails and extending through the collector flanges and the face plate to secure the same to said rails, and a lower pair of fastening devices each engaging the face plate and one of said rails to draw the same into firm engagement with one another; and interengaging means on the collector and the deflector holding the upper portion of the latter against movement away from the face plate, whereby said upper and lower pairs of fastening devices serve to hold the face plate, the collector and the deflector in position on the furnace casing.

7. The hot air furnace of claim 6, wherein the heat exchanger is fixed to the rear of the face plate and forms therewith a subassembled unit that receives support from the casing side walls through said pairs of fastening devices.

8. A heating unit for hot air furnaces, comprising: an upright face plate having a central hole in a lower portion thereof and having a flue gas discharge port in an upper portion thereof; a heat exchanger mounted on the back of the face plate, for transferring heat to air flowing thereover, said heat exchanger having primary heat radiating and transfer surfaces, comprising a lower chamber extending horizontally rearwardly from the lower portion of the face plate and having an opening in its front registering with the central hole in the face plate, through which fuel and air may be introduced into the chamber for combustion therein, said lower chamber being open along its top to enable combustion gases to rise therefrom, and upright duct means connected with said lower chamber along its top for conducting combustion gases upwardly therefrom, said heat exchanger having secondary heat transfer surfaces comprising an upper chamber behind the upper portion of the face plate, said upper chamber having an inlet opening in an upper central portion of one side thereof by which it is connected with said duct means to receive combustion gases therefrom, and being sub-

stantially narrow but having opposite sides which extend substantial distances fore and aft as well as downwardly from the level of said inlet opening, and having a flue gas outlet in its upper front portion connecting with the flue gas discharge port in the face plate; and baffle means in said upper chamber comprising an upper transverse baffle member extending downwardly from the top of said upper chamber at least to the level of the lower edge of the inlet opening thereof and in spaced relation to the front of the chamber but intermediate its inlet and outlet so as to prevent incoming combustion gases from traveling forwardly to said outlet thereof, a substantially upright baffle member in the lower portion of said upper chamber, beneath its inlet and extending rearwardly from the lower portion of said upper baffle member toward the rear of the upper chamber but having a lower rear portion thereof spaced from the rear of the chamber, said lower baffle member cooperating with side wall portions of the chamber at opposite sides thereof to define laterally adjacent compartments in the interior of the upper chamber, one of which compartments opens directly into the inlet space in the upper portion of the chamber rearwardly of said upper baffle member and the other of which compartments communicates with said inlet space only around the lower rear portion of said lower baffle member, and an upright transversely extending wall member closing the front of said one compartment and serving substantially as a downward extension of said upper baffle member so as to cooperate with the latter and with the lower baffle member in constraining combustion gases entering the inlet space of the upper chamber to travel to the outlet thereof via a circuitous route leading downwardly and rearwardly through said one compartment, around the rear of said lower baffle member, forwardly through said other compartment, and then upwardly ahead of said wall member and the upper baffle member toward the outlet of said upper chamber.

9. The heating unit of claim 8, wherein said lower baffle member is a substantially flat plate which occupies a tilted position in the upper chamber, with its bottom adjacent to the side of the chamber having the inlet, and its top adjacent to the opposite side of the chamber.

10. The heating unit of claim 9, wherein said plate has a rear edge which tapers downwardly and forwardly away from the rear of the upper chamber so as to restrict the flow of combustion gases into the narrow upper portions of said other compartment.

11. The heating unit of claim 8, wherein said upright wall member is formed integrally with said plate and is bent to one side thereof at the front of the plate.

12. The heating unit of claim 11, wherein said upper baffle member is removable from the upper chamber through said outlet and the flue gas discharge port, and has an upper end portion which projects forwardly through the top of said outlet and the flue gas discharge port and is detachably connected to the face plate at the front side thereof, and wherein said upper baffle has a bottom portion which is detachably seated upon the upper edge of said upright wall member.

13. A heating unit for hot air furnaces, comprising: an upright face plate having a central hole in a lower portion thereof and having a flue gas discharge port in an upper portion thereof; a heat exchanger mounted on the back of the face plate and comprising a combustion chamber extending horizontally rearwardly from the lower portion of the face plate and having an opening in its front registering with the central hole in the face plate, through which fuel and air may be introduced into the chamber for combustion therein, said chamber being open along its top to enable combustion gases to rise therefrom; upright duct means connected with the combustion chamber along its top, for conducting combustion gases upwardly therefrom; a first hollow radiator fixed to the upper end of the duct means and into the bottom of which the duct means opens to discharge combustion gases thereinto, said first

70
75

radiator extending lengthwise over the combustion chamber and having an outlet in one side thereof through which combustion gases discharge; a second hollow radiator laterally adjacent to said first radiator and extending both downwardly and in fore and aft directions with respect to the outlet of said first radiator, the side of said second radiator which is adjacent to the first radiator having an inlet opening which registers transversely with the outlet of said first radiator, and said second radiator having a flue gas discharge port in its upper front portion; a duct connecting the outlet of the first radiator with the inlet of the second radiator and rigidly joining said radiators together; and baffle means in said second radiator comprising a transverse partition member extending downwardly from the top of the radiator at least to the level of the lower edge of the inlet and in spaced relation to the front of the radiator but intermediate the flue gas discharge port and the inlet, to prevent incoming combustion gases from traveling forwardly toward the discharge port, a substantially upright partition member in the lower portion of the 20 radiator, beneath the inlet, and extending rearwardly from said partition member toward the rear of the radiator but having a lower rear portion thereof spaced from the rear of the radiator, said substantially upright partition member cooperating with walls of the radiator at 25 opposite sides thereof to define laterally adjacent compartments one of which opens directly into the inlet space in the upper portion of the radiator rearwardly of said first

named partition member and the other of which compartments communicates with said inlet space only around the lower rear portion of said second designated partition member, and an upright transversely extending wall member closing the front of said one compartment and serving substantially as a downward extension of said first designated partition member to cooperate with the latter and with the second designated partition member in causing travel of combustion gases entering the inlet space of the 10 radiator to the discharge port via a circuitous route leading downwardly and rearwardly through said one compartment, around the rear of said second designated partition member, forwardly through said other compartment, and then upwardly ahead of said wall member and the first 15 designated partition member to the flue gas discharge port.
